DESIGN FOR A HANDKERCHIEF OR SIMILAR ARTICLE

Anice Mogabgab, New York, N. Y.

Application April 8, 1944, Serial No. 113,180

Term of patent 14 years

(Cl. D3—12)

To all whom it may concern:

Be it known that I, Anice Mogabgab, a subject of the King of Great Britain and a resident of the city, county, and State of New York, have invented a new, original, and ornamental Design for Handkerchiefs or Similar Articles, of which the following is a specification, reference being had to the accompanying drawing, forming a part thereof.

In the drawing:

Fig. 1 is a plan view of one corner of a handkerchief disclosing my new design; and

Fig. 2 is a view in side elevation of the design shown in Fig. 1 looking at the same in the direction indicated by the arrow.

The other three corners of the handkerchief are unornamented.

I claim:

The ornamental design for a handkerchief or similar article, substantially as shown and described.

ANICE MOGABGAB.
